UNITED STATES PATENT OFFICE.

JOHN WILLIAM DUNGEY AND ALFRED ERNEST DROWN, OF LONDON, ENGLAND.

TELEPHONE RECEIVER.

Application filed April 5, 1927, Serial No. 181,137, and in Great Britain April 9, 1926.

This invention relates to instruments such as telephone receivers, wireless loud speakers and the like in which an electromagnet acts on a vibratory metallic diaphragm (the armature) and in which provision is desired for adjusting the air gap between the diaphragm and the pole pieces of the complete electromagnet assemblage for the purpose of adjusting or altering the sensitivity of the instrument.

In such instruments the complete electromagnetic assemblage acting on the diaphragm comprises one or more solenoid windings on a core or cores (hereinafter referred to as the solenoid unit), and a permanent magnet or magnets, (hereinafter referred to as the magnet unit).

The invention comprises an improved method and means for varying the airgap, which permits a considerable simplification in construction and economy of manufacture.

In constructions hitherto proposed the solenoid unit is rigidly connected to the permanent magnet unit and the combined assemblage is given a perpendicular movement directly towards and away from the diaphragm, as by means of a screw, or by a movable wedge, or other means for obtaining a fine adjustment.

In a construction according to the present invention the solenoid is adjusted in an oblique direction relatively to the plane of the diaphragm.

The permanent magnet unit need not be, and preferably is not, secured to the solenoid unit, but may be permanently mounted on the casing, and in such case provision is made to maintain the core or cores of the solenoid unit in contact with the permanent magnet unit during the movement of the solenoid unit.

For example the upper surface of two permanent horse shoe magnets which are fixed to the bottom of the instrument casing may be inclined to the plane of the diaphragm and resilient pressure means provided to maintain the core pole pieces in contact with the magnetic surface during adjustments. A very small movement only is necessary.

The arrangement according to the invention is particularly applicable for casings or shells constructed in accordance with Patent No. 242,737, according to which the shell or casing itself is of magnetic material and

takes the place of the usual permanent-magnet unit, it being only necessary to form a slight incline or flat on the base, on which the core pole pieces are shiftably mounted. 60

Any suitable means may be provided for moving the solenoid unit, for example a screw or lever, or rack and pinion.

Where the permanent magnet unit is fixed to the casing or constituted by the casing 65 (as in Patent No. 242,737), the ends of the core or cores are shaped so that the upper surface remains parallel to the diaphragm plane.

In order furthermore particularly to describe and ascertain the invention, particular constructions in accordance therewith and by way of example, will be more fully described with reference to the accompanying drawings. 70

Figure 1 is a sectional view of a loud speaker embodying the invention.

Figure 2 shows a transverse sectional view of the apparatus shown in Fig. 1.

Figure 3 is a sectional view of a modified form of the invention.

Figure 4 is a plan view of the apparatus shown in Fig. 3.

Figure 5 is a sectional view of a third form or embodiment of the invention. 85

In the various figures the same part is represented by the same reference letter.

In the construction illustrated by Figures 1 and 2 the casing A is constructed in accordance with Patent No. 242,737, the base 90 B thereof having localized areas of magnetization. The base B itself constitutes the permanent magnet unit. The diaphragm C is clamped between the upper periphery of the casing A and a supporting frame D as by screws G. The framework D is provided with three supporting legs E, (only two of which appear in the figure), and may have the usual tubular opening F for the horn. 100

The base B is slightly inclined to the undersurface of the diaphragm C when the latter is in its mounted position. This may, for example, be effected during the construction of the casing.

In the base B a slot H is cut along the slope. Two pole pieces I, which are L-shaped in cross section, are mounted to slide on the pole faces along the inside of the base B. 105

A non-magnetic plate K rests on the flat portions of the pole pieces I, and has shaped

apertures through which the upstanding limbs of the pole pieces pass. The plate K has also a central depending strip K² passing through the slot H, and through 5 a slotted arched spring-plate L. This spring-plate L is held in contact with the under surface of the base B by short pins M through the depending portion K² of the plate K.

10 By this arrangement the pole pieces I are maintained in contact with the pole faces on the base B.

The usual circuit solenoid windings N surround the pole pieces and insulated circuit terminals O are fitted on the casing A.

To adjust the solenoid unit along the slope of the base B the plate K has an upturned flange K¹ to which is secured one end of a screw-threaded adjusting rod P. The rod 20 passes through an internally screw-threaded block Q on the casing A, so that, by rotating the screw, the solenoid unit is adjustable along the slope, and the upper ends of the pole pieces I are consequently adjusted towards and away from the diaphragm.

It will thus be seen that if, for example, the adjusting rod P has 40 threads per inch, and the slope of the base B is 1 in 40 30 relatively to the diaphragm that a substantial adjustment of $\frac{1}{1600}$ of an inch is possible with a complete rotation of the rod P. The above dimensions may obviously be altered according to the fineness of adjustment desired.

In the modified construction illustrated in Figures 3 and 4 the casing A is of non-magnetic material and two permanent horse 40 shoe magnets R, R¹ are rigidly secured on the base B, as by means of two non-magnetic cross strips S and screws S¹, symmetrically with respect to the slot H in the base. The base 1¹ of each pole piece I is 45 sufficiently wide and long to span the opposite ends of the magnets R, R¹, on which the bases 1¹ slide.

The pole pieces I may be resiliently held down as before by a similar non-magnetic plate K, spring plate L, pins M, and similarly adjusted by a screw rod P.

In a further constructional modification illustrated by Figure 5, the pole pieces I may be rigidly mounted together with the 55 permanent horse shoe magnets R on the non-magnetic plate K, the latter being directly mounted on the slotted sloping base B as in the previous constructions, and similarly adjusted by the screw P.

60 Various constructional modifications are obviously possible. For example the adjustment of the solenoid unit might be effected by a lever mechanism, or a rack mechanism in lieu of the screwed rod P.

65 Instead of a sloping base B the upper

surface of the casing on which the diaphragm rests may slope; or a wedge shaped ring may be fitted on the top of an ordinary casing; or the diaphragm may be pressed fan shape, slightly deeper one side than the other.

The means for resiliently holding the solenoid unit on its base support may be varied.

The invention would also be equally applicable for an instrument in which a single 75 pole solenoid unit is employed.

We claim:

1. A telephone receiver comprising a casing, a diaphragm supported on said casing, a flat base for said casing, said base being inclined relatively to the diaphragm, a solenoid unit supported on said inclined base, and means for adjusting the position of the solenoid unit on said base.

2. A telephone receiver comprising a casing, a diaphragm supported on said casing, a flat base for said casing, said base being inclined relatively to the diaphragm, a solenoid unit supported on said inclined base, means for adjusting the position of the solenoid unit on said base, and means for guiding the said solenoid unit during the adjustment.

3. A telephone receiver comprising a casing, a diaphragm supported on said casing, a flat base for the casing, said base having a 95 diametrical slot and being inclined relatively to the diaphragm, a solenoid unit supported on said inclined base, an extension plate carried on said solenoid unit and projecting through the slot in the base, and means for 100 adjusting the position of the solenoid unit upon the base.

4. A telephone receiver comprising a casing, a diaphragm supported on said casing, a flat base for the casing, said base having a 105 diametrical slot and being inclined relatively to the diaphragm, a solenoid unit supported on said inclined base, an extension of non-magnetizable material projecting from the said solenoid unit through the slot in said inclined base, a spring plate secured to the said non-magnetizable extension and maintained in contact with the underside of said base, and means for adjusting the position of the solenoid unit on said base.

5. A telephone receiver comprising a casing, a diaphragm supported on said casing, a flat base for the casing, said base being inclined relatively to the diaphragm, a solenoid winding and pole pieces forming a solenoid unit, a permanent magnet with its poles in contact with the pole pieces of said solenoid unit, and means for adjusting the position of said solenoid unit upon said base.

6. A telephone receiver comprising a casing, a diaphragm supported on said casing, a flat base for the casing, said base being inclined relatively to the diaphragm, a solenoid winding and pole pieces forming a solenoid unit, a permanent magnet with its poles 125

- in contact with the pole pieces of said solenoid unit, a block in the casing having internally screw-threaded means, and a screw-threaded rod for adjusting the position of the solenoid unit upon the inclined base, said rod being secured to said solenoid unit and passing through the internally screw-threaded means of said block to the exterior of the casing.
10. 7. A telephone receiver comprising a casing, a diaphragm supported on said casing, a flat base for the casing, said base being inclined relatively to the diaphragm, a permanent magnet carried by the inclined base, a solenoid unit supported upon said magnet, means for maintaining the poles of the magnet and the pole pieces of the solenoid unit in contact with one another, and means for

adjusting the position of said solenoid unit upon said inclined base.

20

8. A telephone receiver comprising a casing, a diaphragm supported on said casing, a flat base for the casing, said base being inclined relatively to the diaphragm, a permanent magnet carried by the inclined base, a solenoid unit supported upon said magnet, means for maintaining the poles of the magnet and the pole pieces of the solenoid unit in contact with one another, means including a screwed rod for adjusting the position of said solenoid unit upon said base, and means for guiding the solenoid unit during the adjustment.
